UNITED STATES PATENT OFFICE

2,446,713

HAND RIVETER

William E. Melick, Toledo, Ohio

Application August 6, 1946, Serial No. 688,776

7 Claims. (Cl. 218—19)

1

This invention relates to riveting tools, and particularly to such tools of the hand-operated type having a part adapted to be projected through a hollow rivet from the side of the material to be riveted from which the rivet is initially introduced and to be operated to upset or outwardly flange the end of the rivet at the opposite side of the material in a manner to firmly hold the separate lapping material members in assembled relation.

An object of the invention is the provision of a novel hand tool of this character that is simple and inexpensive in construction and easily and quickly operable to effect an efficient riveting operation.

The invention is fully described in the following specification, and one embodiment thereof illustrated in the accompanying drawings, in which—

Fig. 1 is a side view of a riveting tool embodying the invention, with the handles partly broken away and with the stem expanding plunger retracted; Fig. 2 is a forward end view thereof; Fig. 3 is a fragmentary view of the parts shown in Fig. 1, with parts in section and with the stem member of the tool in the act of being projected through a rivet; Fig. 4 is a fragmentary detail showing the stem projected completely through a rivet with the expanding plunger in position for expanding the stem within the rivet and with the opposing thrust parts of the tool in initial rivet upsetting position; Fig. 5 is a view similar to Fig. 1, with parts broken away and with the opposing rivet engaging parts in completed upsetting position; Fig. 6 is a perspective view of the stem member of the tool, and Fig. 7 is a perspective view of the expanding plunger with the control ring removed.

Referring to the drawings, 1 and 2 designate handle members which are crossed and pivotally connected at 3 in the manner of a pair of pliers and have the long handle ends *a* and the short power ends *b*, with both spaced apart as shown. It is apparent that an inward movement of the handle parts *a*, accomplished by a tightening of the grip of a hand holding the tool, will cause the parts *b*, which are normally spaced a considerable distance apart, to have relative inward movements imparted thereto to narrow the space therebetween.

The free ends of the handle parts *b* are connected by two sets of opposing toggle links 4 and 5 connected at their outer ends by pivots 6 to the respective handle parts. The inner ends of the inner or rear pair of links are pivotally connected coaxially to the member 7 at opposite sides there-

2

of, while the inner ends of the other set are pivotally connected coaxially to a thrust or anvil member 8. It is thus apparent that an inward or contracting movement of the handle parts *b* will tend to collapse the toggle connections and force the members 7 and 8 outward from each other, while an outward or expanding movement of said parts will cause a straightening movement of said connections to force the members 7 and 8 inward toward each other.

10 A stem 10 having its forward end portion forked to permit contraction from normal diametrical size is projected through the two members 7 and 8 and projects in advance of the latter and is freely slidable therein. The rear end of this stem is threaded through the rear member and locked thereto by a nut 11 so that the stem will have movements with such member. This also permits adjustment of the stem to suit the length 15 of the rivet to be acted on. The forward end of the stem 10 is forked for a considerable portion of its length by longitudinally splitting it, by sawing or otherwise, to provide a plurality of normally spaced fingers 12 with slots 13 therebetween. Each finger is provided at the outer side 20 of its free end portion with a lateral projection 14 which cooperates with those of the other fingers to form an enlargement at the forward end of the stem for coaction with the outer end of a rivet through which projected to effect an upsetting or clinching thereof as hereinafter described.

25 The stem fingers are held in expanded relation within a rivet by a plunger 15 mounted for longitudinal sliding movements in the stem and having a plurality of side flanges corresponding in number to the slots in the stem and fitting therein. The rear end portions of these flanges are projected slightly beyond the outer edges of the stem slots and threaded as shown at 17 to permit a thumb-piece 18 of ring-form to be threaded thereon between the members 7 and 8 and in encircling relation to the stem. The plunger 15 is shorter than the slotted portion of the stem to enable it to be retracted a distance therein to permit inward relative springing or collapsing of the enlarged end of the stem sufficient for its insertion through a rivet as shown in Fig. 3. When the stem has been inserted through a rivet, the plunger is moved forward by hand to the end of the stem to effect an expansion thereof to normal size and prevent withdrawal of the stem enlargement through the rivet, as shown in Figs. 4 and 5.

30 In the use of the tool a rivet 20, with only one

end flanged, is inserted through registering holes in two lapped material strips 24 from the exposed side thereof, and the tool stem 10, with the plunger 18 retracted, is then collapsed at its free end and inserted through the rivet to position its enlargement 14 beyond the unflanged end thereof. At the same time the thrust member 8 is in position to bear against the inner flanged end of the rivet. The plunger 18 is then moved forward by pressure applied to the knurled ring 16 to the position shown in Figs. 4 and 5, thus holding the stem in its normally expanded form to prevent withdrawal of its enlarged end through the rivet. Pressure now applied to portions *a* of the handles 1 and 2 will cause the toggle members 4 and 5 to move apart. This action moves the member 8 forward into holding contact with the adjacent or flanged end of the rivet and at the same time draws the stem 10 rearward to force its enlargement 14 into upsetting engagement with the opposed or outer end of the rivet. In this manner, powerful opposing pressures can be applied to the two opposing rivet-engaging thrust parts 8 and 14 to effect a clinching of the rivet without movement of the rivet in the material being riveted and with comparative ease on the part of the operator.

I wish it understood that my invention is not limited to any specific construction, arrangement or form of the parts, as it is capable of numerous modifications and changes without departing from the spirit of the claims.

Having thus described my invention, what I claim as new, and desire to secure by United States Letters Patent, is:

1. In a tool of the class described, a pair of handles in pivoted plier-like connection with laterally spaced parts, two sets of toggle links connecting said parts for opposed breaking and straightening movements, a stem carried by and projected from one set of said links across the other set, said stem having its projected end portion longitudinally split to permit lateral collapsing to reduce its diameter and being provided with an enlargement for projection through a hollow rivet when the stem end is contracted and for thrust engagement with the outer end of the rivet when the stem end is expanded, means movable lengthwise of the stem to hold the stem end expanded, and a thrust member on said other pair of links for acting against the adjacent end of a rivet when the stem is drawn inwardly to cause its enlargement to have upsetting coaction with the opposite end of the rivet by outward opposing movements of the two sets of links.

2. In a tool of the class described, a stem having a longitudinally split laterally contractible end portion with an enlargement at such end and adapted when contracted to be projected through a hollow rivet, means carried by the stem and movable lengthwise thereof into and out of position to prevent contraction of the stem after projection of its enlargement through a rivet, a thrust member, and toggle means including two sets of opposing links connected to said stem and operable by opposed breaking action to cause said member and stem enlargement to impart opposing pressures against opposite ends of a rivet

through which the stem is projected and cause an upsetting of at least one end of the rivet, and handles of pivoted plier-like form carrying said toggle connections and operable to impart opposed inward straightening or outward breaking movements of said sets of links.

3. In a tool of the class described, two sets of laterally opposing toggle links, means connected to the outer ends of the links of each set and operable to impart opposed breaking and lengthening movements in unison to both sets of links, a stem longitudinally movable by said movements of one set, a thrust member carried by the other set at the point of pivotal connection of its links, said stem having an outer end enlargement and being laterally contractible at such end for projection of the enlargement through a hollow rivet, means carried by the stem and movable into and out of position to prevent contraction of its end, and means connected to said two sets of toggle links and operable to force said thrust member against one end and said stem enlargement in upsetting engagement against the other end of a rivet through which the stem is projected.

15 4. A combination as called for in claim 3, wherein said operating means is plier-like in its action and has its short arms laterally spaced and connected by the toggle sets.

20 5. In a tool of the class described, a stem having an end enlargement and longitudinally split to permit lateral contraction of such end for projection of the enlargement through a hollow rivet, means carried by the stem and movable into and out of position to prevent said contraction, a thrust member for engagement with the opposite end of a rivet on the stem from said enlargement, and means including double sets of oppositely moving toggles one connected to said stem and the other to said thrust member and operable to impart opposing rivet clinching movements thereto.

25 6. A combination as called for in claim 5, wherein the stem is adjustably attached to the toggle set with which connected to permit lengthening or shortening of the stem projection therefrom to suit the length of a rivet to be acted on.

30 7. A combination as called for in claim 5, wherein said means includes crossed pivotally connected levers for operating the toggle sets.

35 8. A combination as called for in claim 5, wherein the stem is longitudinally split to permit lateral contraction of such end for projection of the enlargement through a hollow rivet, means carried by the stem and movable into and out of position to prevent said contraction, a thrust member for engagement with the opposite end of a rivet on the stem from said enlargement, and means including double sets of oppositely moving toggles one connected to said stem and the other to said thrust member and operable to impart opposing rivet clinching movements thereto.

40 9. A combination as called for in claim 5, wherein the stem is longitudinally split to permit lateral contraction of such end for projection of the enlargement through a hollow rivet, means carried by the stem and movable into and out of position to prevent said contraction, a thrust member for engagement with the opposite end of a rivet on the stem from said enlargement, and means including double sets of oppositely moving toggles one connected to said stem and the other to said thrust member and operable to impart opposing rivet clinching movements thereto.

45 10. A combination as called for in claim 5, wherein the stem is longitudinally split to permit lateral contraction of such end for projection of the enlargement through a hollow rivet, means carried by the stem and movable into and out of position to prevent said contraction, a thrust member for engagement with the opposite end of a rivet on the stem from said enlargement, and means including double sets of oppositely moving toggles one connected to said stem and the other to said thrust member and operable to impart opposing rivet clinching movements thereto.

50 11. A combination as called for in claim 5, wherein the stem is longitudinally split to permit lateral contraction of such end for projection of the enlargement through a hollow rivet, means carried by the stem and movable into and out of position to prevent said contraction, a thrust member for engagement with the opposite end of a rivet on the stem from said enlargement, and means including double sets of oppositely moving toggles one connected to said stem and the other to said thrust member and operable to impart opposing rivet clinching movements thereto.
